UNITED STATES PATENT OFFICE.

JAMES A. GRUNDY, OF PHILADELPHIA, PENNSYLVANIA, ASSIGNOR OF ONE-HALF TO
JOHN BROMLEY & SONS, INCORPORATED, OF PHILADELPHIA, PENNSYLVANIA, A
CORPORATION OF PENNSYLVANIA.

JACQUARD-CARD-PUNCHING DEVICE.

1,318,662.

Specification of Letters Patent.

Patented Oct. 14, 1919.

Application filed February 20, 1919. Serial No. 278,208.

To all whom it may concern:

Be it known that I, JAMES A. GRUNDY, citizen of the United States, residing in the city of Philadelphia, State of Pennsylvania, have invented certain new and useful Improvements in Jacquard-Card-Punching Devices, of which the following is a full, clear, and exact description, reference being had to the accompanying drawings, forming a part of this specification.

The invention has for its purpose, the perforating or punching of jacquard cards, used in Jacquard looms and similar devices, and more particularly, has for its purpose, the simultaneous punching of two or more cards which are to be subsequently coördinately used upon such devices, whereby a plurality of patterns to be woven may be simultaneously controlled and so combined as to considerably shorten the length of the usually endless chain of cards.

It is the present practice in perforating jacquard cards to utilize finger controlled punching heads with twelve and occasionally sixteen punching plungers. Inasmuch as all of the finger operated control keys must be held in locking position by the fingers during the time of the perforating or punching operation of the machine, it is impossible in such structure to remove any of the fingers from certain of the operated keys in order to operate certain others without the first-mentioned keys returning to ineffective position, and consequently, it has been difficult heretofore to operate more than twelve keys by the finger control and holding method, while extraordinary skill is required in manipulating sixteen keys.

The invention herein disclosed, therefore, has for its principal objects the overcoming of the above difficulties and also for the permitting of the use of an indefinitely large number of punches either in a single system or in multiple, whereby the finger keys may be operated and when so operated, will remain in punch-locking position when the fingers are removed from said keys to other keys until the operator operates the perforating mechanism, and subsequently the means for positively returning the keys to ineffective or inoperative position.

In attaining these objects I preferably utilize existing perforating means, known generally under the name of "Royal piano

heads", and adapting the same, in a manner hereinafter more fully disclosed, to the particular purposes indicated.

Another object is to enable one to utilize a finger keyboard from which to control the locking rods rather than directly moving the rods into locking position as in the old form of device.

A further object is to employ an electrical system controlled from said keyboard and effective to influence the selected and proper movement of the locking pins by means of electromagnets connected in the circuits of the system.

A further object is also to provide certain visible signals, as colored lights, operable to indicate the particular circuit or circuits, and pin or pins controlled from the finger operated keyboard.

A further object is to provide a special form of circuit closing means for so controlling the circuits that the chance of interference of the circuits of one set of the perforating devices with another set is absolutely avoided.

A further object is to provide means whereby the circuit closing devices may be all returned to the neutral or the inoperative position by the operation of a single finger operated means.

A still further object is to provide means whereby in the event that it is desired to repeat a design or pattern in any set of the perforating devices, the circuit closing means of the other circuits may be broken or returned to neutral or inoperative position, while those to be repeated remain in operative connection for the next punching operation, thereby avoiding the necessity of again manipulating corresponding keys therefor upon the keyboard.

A still further object is to so construct the device that the switches or the circuits may be controlled in a converse manner, that is, all the circuits may be initially closed and the pattern or design to be produced effected by the opening of certain of the circuits by the returning of the corresponding keys on the key-board to neutral position.

A still further object is to employ supplementary circuit closing means, of various forms which may be operated in connection with or in lieu of the finger keyboard circuit means, when it is desired to produce a par-

ticular design effect or pattern, such as a twill, a satin, a honeycomb, or the like.

A still further object is to so arrange and connect the circuit controlled means that a composite pattern or design may be produced from the combined operation of both the supplemental and individual selective switch means.

Another and still further object is to enable me to perforate correlated cards in multiple, the particular form of means chosen for illustration here operating upon two cards of which one contains the pattern of the other with an additional pattern.

These and other objects and advantages flowing from this invention will be disclosed in the following specification and appended claims.

For the purpose of carrying out the invention, one form of device or embodiment of the invention is more fully described in the specification and illustrated in the drawings.

Referring now to the drawings, in which the same reference characters indicate the corresponding elements in the various views:

Figure 1 is a plan view, in diagrammatic form, of a pair of punching heads with the connected electromagnets and of the finger keyboard, as well as the wiring diagram forming the first and second circuits of each set;

Fig. 2 is an end view, partially in section of the keyboard and circuit closing mechanism.

Fig. 3 is a view partly in transverse section of the perforating device;

Fig. 4 is a fragmentary illustration of the usual form of chart used in connection with the finger keyboard for obtaining the patterns punched in the cards;

Fig. 5 is a broken plan sectional view of the keyboard showing more particularly the supplementary circuit closing means.

Fig. 6 is a transverse section of the means shown in Fig. 5.

Figs. 7 and 8 show two of the contact bars that may be used in the supplementary circuit closing means shown in Figs. 5 and 6 as well as that shown in Figs. 9 and 10.

Fig. 9 is a view similar to Fig. 5 of a modification of the means shown therein.

Fig. 10 is a transverse section of the means shown in Fig. 9; and,

Figs. 11, 12 and 13 are fragmentary portions of design charts showing examples of the type of pattern that may be obtained with the supplementary circuit closing means shown in Figs. 5, 6, 9 and 10.

The mechanism employed comprises two punch heads, 1 and 2, usually termed "Royal piano heads," which are each provided with sixteen perforations, 3 and 4, and in which are adapted to vertically reciprocate the 65 perforating or punching plungers 5 and 6.

The heads are also provided with lateral perforations 7, 8, 9 and 10 through which are adapted to reciprocate the locking rods 11, 12, 13 and 14 connected at an end thereof to the armatures 15, 16, 17 and 18 of the electromagnets 19, 20, 21 and 22, suitably mounted upon brackets 23 secured to the undersurface of the table 24. When any of the electromagnets are energized, the armatures are caused to swing about the pivots 25 toward the cores 26 of said electromagnets and reciprocate the locking rods through their corresponding lateral perforations, provided in the heads 1 and 2, to interpose the ends 27, 28, 29 and 30 thereof immediately above the upper ends 31 of the punching plungers, the coil springs 27', 28', 29' and 30' operating to return said locking rods to ineffective or inoperative positions when the electromagnets are deenergized. Any tendency of the punching plungers to subsequently move upwardly is thus impeded by said ends 31. Consequently, upon a downward movement of the heads 1 or 2, and the punching plungers, toward a stationary body, the lower end 32 of a punching plunger, will contact therewith and the locked punches operated to perforate the body while the other punches will be caused to retreat through and in the perforations 3 or 4. This body is usually in the form of a sheet of card-board, 33 or 34 which is intermittently fed between the die plates 35 and 36, through the holes 37 and 38 of which the ends of the punching plungers are adapted to be guided during the punching operation.

The heads 1 and 2 are also provided with larger perforations 39 and 40 in which are adapted to reciprocate punching plungers 41 and 42 for the purpose of perforating peg holes in the cards at suitable places. These plungers are also controlled by locking rods 43 and 44 controlled by electromagnets 45 and 46 mounted upon the lower side of the table in a manner similar to the electromagnets hereinbefore described. The ends 47 of these punching plungers are also guided through the holes 48 in the die plate 35 during their punching operation.

Upon the table 24 is provided a finger operated keyboard or switchboard which is utilized for the purpose of controlling the locking rods referred to above. Inasmuch as there are sixteen pattern punching plungers in each head, two sets of finger keys, 49 and 50, of which there are sixteen in each set, the keys 50 of one set being operated for the control of the punching plungers in the head 1 and the finger keys 49 of the other set being operated for the purpose of controlling the punching plungers in both heads 1 and 2.

The finger keys are rigidly mounted upon the vertically reciprocable stems 51 and 52, 130

passing through the table and pivotally secured to the ends 53 and 54 of the cross-bars 55, which are fulcrumed upon a shaft 56. To the ends of the cross bars are pivotally connected the links 57 and 58 in connection with contact plungers 59 and 60, the ends of which are adapted when reciprocated to contact with and close the gaps between the spring contacts 61 and 62, suitably mounted upon and insulated from the table or base, for the purpose of closing an electrical circuit including said spring contacts.

At the end of the switchboard is also provided the addition finger keys 63 and 64 connected to the cross-rod 65, circuit closing means identically the same as that shown in Fig. 3. This additional circuit closing means is utilized for the purpose of controlling the circuits to the electro-magnets 45 and 46 and the large punches 41 and 42 for the peg holes referred to hereinbefore.

Located above to overlie the cross bars 55 and 65 are the horizontal bars 66 and 67 secured to the vertical rods 68 and 69, reciprocable through the table and provided at the upper ends thereof with the finger bars 70 and 71, which extend across the full width of the finger-board. The lower ends of the rods 68 and 69 pass through the lower partition 72 of the table or machine frame to be guided therethrough and are surrounded by the coiled springs 73 and 74, reacting at one end against the stationary bosses 75 and at the other end against the collars 76 and 77 suitably secured to said rods. The cross arm 78, which is provided at the ends thereof with the bores 79 and 80 through the rods 68 and 69 are adapted to slide, is located immediately above the collars 76 and 77 and is connected by the link 81 to the finger operated lever 82 pivotally mounted to the table or machine frame at 83. Surrounding the contact plungers 59 and 60 are located the sleeves 84, 85, 86 and 87 which may be made of any suitable nonconducting material, the spring contacts 61 and 62 being secured to the sleeves 84 and 85 by any suitable means, such as screws.

The shank portions 88 and 89 of the spring contacts may be in the form of bus-bars extending the full length of the switchboard and respectively connected to the leads 90 and 91 from the electrical feed wires 92 and 93, the corresponding shanks of the contact springs of the additional switches at the end of the switch-board being both connected to the lead 90.

Upon the table 24 and opposite each of the finger keys 49 and 50, are disposed colored lights 94 and 95, those adjacent to the keys 49 being of one color, in this case, red, and those disposed adjacent to the keys 50 being of another color, in this case, green.

The electric wire system utilized for carrying out the operation of this invention is

a three wire system comprising the main feed wires 92, 93 and 96 the potential between the wires 92 and 93 being equal to that between wires 93 and 96 and one half that between the wires 92 and 96 and for the purpose of exemplification the potential that may be used is that of a voltage of six volts between the wires 92 and 93, as well as, between the wires 93 and 96 and a voltage of twelve volts between the wires 92 and 96.

This system is useful where it is desired to operate electro-magnets in various combinations, that is, where one or more are thrown in circuit in series. Where one pair of electro-magnets (see Fig. 3) only is included in a circuit, the latter may be made from the wire 93 to wire 96 between which there is a voltage of six volts, which is sufficient to operatively energize a single pair of electro-magnets, while on the other hand, when it is desired to include in a circuit two pairs of electro-magnets in series this circuit should be made from the wire 92 to wire 96 between which there is a potential of twelve volts, which is ample to effectively energize said electro-magnets.

The red lights are connected in a closed shunt with the circuits of the electro-magnets 19, 20, 21 and 22 and are used to indicate that the electro-magnets, 19 and 21 or 20 and 22, controlling the corresponding punches of each head, are in series and are energized and that the corresponding perforations will be made in both cards 33 and 34. The green lights are connected in an open shunt circuit with the circuits of the electro-magnets 19 or 20 only and, therefore, indicate which of the electro-magnets 19 or 20 is in circuit and energized and that the corresponding perforations will be made in the card 33 only. This shunt circuit leads through the contacts 97, 98, 99 and 100 or 101, 102, 103 and 104, as the case may be, of which the contacts 97, 99, 101, 103 are mounted upon the locking rods 11, 13, 12 and 14 respectively and movable therewith, toward or from the stationary contacts 98, 100, 102 and 104 fixed to the table 24.

The contacts 97, 98, 101 and 102 are normally out of contact and the contacts 99, 100, 103 and 104 are normally in contact. Whenever a circuit is closed to operate any of the punches of head 1 the locking rods therein will carry a contact 97 or 101 to the stationary contact 98 or 102 to thereby close the circuit, the other contacts remaining in their normally closed position, and the corresponding green light indicates the particular holes punched. If however, a circuit is closed to operate any of the corresponding punches in both heads 1 and 2, notwithstanding the fact that the contacts 97, 98, 101 and 102 will operate as described above, the contacts 99, 100, 103 and 104, however, will separate and this circuit broken, since

the locking rods in head 2 are caused to move into locking position thereby carrying the contacts 100 and 103 away from the stationary contacts 99 and 104. This prevents 5 the lighting of the green lights accordingly. Inasmuch as the red lights are in shunt with the energizing circuits of the electro-magnets they serve to indicate in the manner heretofore stated.

10 From the above description, it is apparent that when one of the keys, as for example 49, is depressed to the dotted line position shown in Fig. 2, the cross bar 55 is caused to turn about the shaft 56 and the contact 15 plunger 59 moved downwardly through the sleeve 86 into the gap between the spring contact 61 to engage therewith whereby an electrical circuit is closed. Operation of a key 50 will similarly swing a cross bar 55 20 about the shaft 56 in the opposite direction and close another circuit by movement of another plunger 66 in contact with the other spring contacts 62. Those first mentioned were on the side of the board termed the 25 "red" side and those last mentioned, on the side of the board termed the "green" side.

After a number of keys on either or both 30 sides of the finger board have been operated to close the circuits in the manner above described and the punching apparatus has 35 been operated, and in the event it is desired to return all of the cross bars 55 to the horizontal position shown in Fig. 2 thereby breaking all of the circuits the operator presses down upon the lever 82 thereby 40 causing the link 81 and the cross arm 78 to be lowered. The movement of the cross arm 78 is thereby imparted to the rods 68 and 69 through the collars 76 and 77 fixed thereto, 45 and finally to the horizontal rods 66 and 67 which come in contact with the upper edges of the cross bars 55 and 65. This downward movement of the horizontal bars will bring the cross bars to the horizontal or neutral position. If, however, it is only desired to 50 swing the cross bars of one side of the finger board to neutral position to break the circuits of one set of electro-magnets and to repeat the operation of those on the other side, the operator will not in that case operate the lever 82, but will, for example, press down the finger bar 70, thereby bringing the horizontal bar 66 into contact with the cross bars 55 and 65 which have been operated 55 to close the circuits on the "red" side, the other cross bars which are connected to the plungers closing the circuits on the "green" side not being affected thereby. This operation is possible by reason of the 60 fact that as the finger bar 70 is depressed and the rods 68 secured thereto are lowered, the collars 76 will separate from the end of the cross arm 78 and compress the coil springs 73 without any effect upon the cross arm and the other members, 71, 77, 69 and 74.

Fig. 1 is referred to as showing, in a diagrammatic disposition, the distribution of the electro-magnets in respect to the punching plungers, the electric wiring diagram and also a plan view of the finger keyboard 70 or switchboard. It has been deemed only necessary to show the wiring diagram for the circuits controlling the first and second punching plungers of each head, as well as the wiring for the signals for the same, and 75 also the wiring of the circuits controlling the large punching plungers for punching the peg holes. The wiring for the other circuits follow the same plan and their illustration is deemed unnecessary, the leading 80 ends of these circuits merely being shown. In tracing out the circuit for the first punch of both heads, the operator depresses the first key 49 of the set upon the "red" side 85 of the key-board and closes the circuit leading from the feed wire 92 to the busbar 105, spring contacts 61, contact plunger 59, the wires 106 and 107, electro-magnets 21, wire 109, to the electro-magnets 19, wire 110 and wire 111 to the feed line 96. One of the 90 "red" lights 94, corresponding to this circuit is connected in shunt therewith, across the wires 106 and 109 leading to and from the electro-magnet 20, by the wires 112 and 113. In following the circuit for the first 95 plunger upon the head 1, only, the operator depresses the key 50 of the set upon the "green" side of the finger key-board and closes the circuit leading from the feed wire 93, to the bus-bar 114, spring contacts 62, 100 contact plunger 60, wires 113 and 109, electro-magnets 19, wires 110 and 111 to the feed line 96. The "green" light circuit corresponding to this operation leads from the bus-bar 114 to the light 95 and thence to the 105 wires 117 and 118 to the movable contact 99 mounted upon one of the locking rods 13, stationary contact 100, wire 119, movable contact 97 mounted upon one of the locking rods 11, stationary contact 98, wires 120, 110, and 111 to feed wire 96. From the above, it will be noted that in the case of 110 operating the circuit from the "red" side of the finger board, the electro-magnets 20, corresponding to the first punch hole on the 115 head 2, as well as the electro-magnets 19 corresponding to the first hole on the punch head 1 are in circuit in series and are both operated whereby the first plungers of both heads are locked so as to perforate the first 120 hole of a row in each of the cards 33 and 34. In the case of closing the first circuit on the "green" side of the finger board, the corresponding "red" circuit cannot be closed, but the "green" circuit is closed 125 through the electro-magnets 19 of the first punch of the head 1 only, thereby punching the first hole of a row in the card 33. The other circuits are controlled on both sides 130 of the finger boards in exactly the same

manner as described above. For the purpose of operating the large punching plungers for the peg perforations, the additional switch operating means, provided at the end 5 of the switch board is operated upon either side of the board in a manner similar to operating the other circuit closing means described above. In this case the circuit leads from the feed wire 92, to wire 90, to either 10 bus-bar 105 or 114, through either plunger contact switches 121 and 122, wire 123, electro-magnets 45, wire 124, electro-magnets 46, wires 125 and 111 to feed line 96. This circuit closing means is operated only at 15 intervals occurring between the patterns upon the cards, and it is optional as to which of the switches 122 is operated.

For the purpose of directing the operator in the manner of pressing the finger keys 49 20 and 50 to produce a desired pattern, a chart has been composed from which the combined 25 readings may be read for operating the keys in a proper selection and to produce the result in patterns upon the cards 33 and 34 of which the pattern on one card is included or duplicated in the pattern on the other card. An example of the chart used, is shown 30 in Fig. 4. The symbol "X" indicates the pressing of a key 49 on the "red" side and the symbol "O" indicates the pressing of 35 the key 50 on the "green" side, the blank space indicating no operation of any key. The vertical columns are numbered from 1 to 16, corresponding to the first to the sixteenth 40 punch holes in both heads 1 and 2, as well as to the first to the sixteenth finger keys of each set on the finger board. The horizontal rows represent cards, the first row of holes for the first set of cards (here 45 a pair) being indicated in the first section of the left hand side of the chart as shown in Fig. 4. The second row of holes being represented by the first horizontal row in the second section of the chart and the third 50 row of holes represented by the first horizontal row in the third section, and so on indefinitely for the number of rows that may occur in or be chosen for a card. After the peg holes are punched and the card strip 55 moved a sufficient distance, for starting a design upon a second set of cards, the second horizontal row of the chart is read from left to right, each section in said row representing as indicated above, a row of holes in the cards.

For example, in reading the chart shown, the operator will for punching the first row of holes for the first pair of cards, press the keys from 1 to 16 as follows: Red, 1, 2, 4 60 and 6, green 7, red 10, 12, 15, 16; second row green 1 red 2, green 3, 5, red 6, 7, 8, 9, green 10, red 11, 13, green 14, 15, red 16, and so on for the succeeding rows, until the length of a set of cards is completed. In perforating 65 the second set of cards, the operator

reads upon the second horizontal row from left to right, similarly to the manner indicated above.

In addition to the above means it frequently occurs that a pattern of more or less 70 uniform or symmetrical design is to be controlled, and in order to facilitate operating the circuits therefor and also to save time, I have provided at each side of the finger keyboard supplementary circuit closing 75 means, as is shown in the simpler form in Figs. 2, 5 and 6 and in a more elaborate form in Figs. 9 and 10.

In the form shown in Figs. 2, 5 and 6 the supplementary circuit closing means 80 comprise pivoted supports 126 and 127 mounted upon the table 24. The upper ends of the supports carry laterally slotted beams 128 and 129 in the slots of which slidably 85 repose the comb bars 130 and 131 of electrically conducting metal, such as brass, copper, or the like. These comb-bars are provided with lateral teeth like contact points 132 and 133 adapted to successively 90 contact with the shanks 61' and 62' of the spring contacts 61 and 62 respectively as the comb-bars are moved longitudinally in the grooves or slots of the beams 128 and 129. These contact points are distributed along 95 the comb-bars in certain spaced relation determined upon the relation of the circuits to be controlled. In the form shown in Figs. 5 and 7, the contact points are arranged to contact with the first, fourth, seventh, tenth, 100 thirteenth and sixteenth shanks 61' and 62', 105 in the first circuit closing position of this particular comb-bar. In the second circuit closing position this form of comb-bar, closes the circuits for the second, fifth, eighth, eleventh and fourteenth shanks 61' and 62', and 110 so on indefinitely.

In Fig. 8 the contact points are shown as arranged in the order to close the circuits of the first, seventh and thirteenth shanks in the first circuit closing position; the second, eighth and fourteenth shanks in the second position; the third, ninth and fifteenth in the third position, and so forth. The operations described will produce a pattern effect termed a "twill" and shown, for the comb-bar of Fig. 8, in the design chart of Fig. 11, the symbols "x" showing the form of twill produced. If in operating these comb-bars, 115 that on the "red" side of the switch-board be successively moved in the direction from the first to the sixteenth shanks 61' and that on the "green" side be simultaneously moved from the sixteenth to the first shanks 62', the combined pattern effect will be of a "honey-comb" design as is shown in the combined arrangement of the symbols "x" and "o" in the design chart shown in Fig. 11. 120

The shanks 61' and 62', as is clearly shown in Figs. 5 and 9, are embedded in the insulating material of the key-board so that the 130

faces of both the shank pieces and the insulating material are co-incident and offer a continuous and smooth surface, over which the contact points of the comb-bars may move. Any intermediate position of the comb-bars so that the contact points will lie between the shanks 61' or 62', or even beyond the same at the end of the switch-board, has the effect of opening all of the circuits of the comb-bars so positioned.

The springs 134 and 135 are secured to an end thereof to the supports 126 and 127 and at the other end to fixed uprights 136 and 137 rigidly secured to the table 24. These springs serve the purpose of constantly urging the beams and comb-bars toward the shanks 61' and 62' so that the contact points thereof shall bear with the pressure requisite to make a good electrical contact between the points and the shanks, as the bars are successively moved, in the manner described above.

In the beams are also provided recesses in which are disposed springs 138 and 139 the ends of which resiliently bear against the rear edges of the comb-bars 130 and 131 and the centers of which are suitably secured to the beams as by screws 140 and 141. These springs also aid in pressing the comb-bar contact points against the shanks 61' and 62', and also compensates for variations in the widths of the bars used as well as for wear thereof.

The bars are also each provided with perforations or depressions 142 with which spring detent means 143 of any suitable type may coöperate to temporarily lock the bars in their successive positions but not with such engagement as to prevent movement of the bars by hand.

At the end of the beams 128 and 129 are provided contact plates 144 and 145 adapted to engage with the rear edges of the comb-bars, whereby electrical current leading in through the leads 146 and 147 may be conducted to the comb-bars 130 and 131 for the purposes mentioned above.

In operation, the operator lowers the beams 128 and 129 about pivots of the supports and places in the slots thereof a set of comb-bars 130 and 131 and the beams are then permitted to swing up to position, under the influence of the springs 134 and 135, where the contact points of the comb-bars are pressed against the surface in which the shank contacts are embedded. The bars may then be moved longitudinally in the beam slots to present the contact points to the shanks whereby certain related circuits may be closed. If the type of bar shown in Fig. 8 be used, the first, seventh and thirteenth circuits, on the "red" side of the switchboard, will be closed as represented by the symbols "x" in the lower row 65 of the design chart shown in Fig. 11. On

moving the bar to the next position the second, eighth and fourteenth circuits will be closed, and thence accordingly for the full range of movement of the bars. This will effect a "twill" as represented by the symbols "x" only. If, however, at the same time the bars on the "green" side be operated in the reverse direction, as from the sixteenth to the first circuits, at the same time as the "red" side bar is operated, the combined effect will be that shown by the arrangement of the symbols "x" and "o" in Fig. 11, which is called a "honey-comb" pattern. If, however, the "comb-bar" for the "green" side be started at an advanced shank contact, as for example at the fourth rather than the first, when the "comb-bar" for the "red" side is started at the first shank contact, and both are moved in the same direction, the combined effect obtained is shown in the chart of Fig. 12, which is a "twill" pattern. If on the other hand the comb-bars on the "red" and "green" sides are advanced at different rates the pattern lines of one will cross the other and, therefore, produce a "satin" effect as shown in Fig. 13.

The charts in Figs. 11, 12 and 13 are shown more for illustrating the type of design or pattern effect obtained rather than the chart from which the operator reads. The chart from which the operator controls the operation of the comb-bars is in fact similar to that shown in Fig. 4 but the designs shown in Figs. 11, 12 and 13 are arranged to more clearly show the resultant relation of the design points controlled.

The device shown in Figs. 9 and 10 is in all respects the same as that shown in Figs. 5 and 6 with the exception that a plurality of comb-bars 130' and 131' may be placed in each beam and the beams are provided with mechanical means whereby the bars may be moved definite distances in one direction or the other by the simple manual movement of said means.

These beams are, therefore, provided with longitudinal slide ways 148 and 149 in which are adapted to slide the slide-bars 150 and 151. At the free ends of the latter are pivotally attached the spring pressed pawl-hooks 152 and 153 adapted to engage with the teeth 154 and 155 provided upon the rear edges of the comb-bars. The other ends of the slide bars are provided with finger buttons 156 and 157 projecting upwardly above the top of the beams. Springs 158 and 159 are nested in the ends of the slide-ways for operation against the slide-bars to return the same to initial position, when the same have been manually operated as indicated above.

When it is desired to reverse the movement of the comb-bars, the pawl-hooks 152 and 153 may be thrown out of engagement 130

by the arm 160 or 161 of the release levers 162 or 163 as the latter are manually moved by the handle portions 164 or 165. Detent projections 166 carried on each lever are 5 adapted to engage depressions 167 on the beams for the purpose of holding the levers in their alternate positions. When the pawl-hooks are thus dis-engaged from the bars at one end thereof, the release lever at the 10 other end may be operated to permit the re-engagement of the pawl-hooks 152' and 153' with the teeth 154' and 155' and manual manipulation of the finger buttons 156' and 157' will be effective to move the bars as 15 in the first operation described except in the reverse direction.

It will be noted that the arms 160 and 161 of the release levers are provided with 20 detent hooks 168 and 169 engageable with the teeth 154, 155, 154' and 155' of the comb-bars to act as detent pawls therefor. When the release levers are operated to disengage the pawl-hooks these detent hooks will also be simultaneously disengaged.

25 The circuit leads 146' and 147' are connected to the contact plates 144' and 145' which are suitably secured to the end of the insulating material of the switch-board and which also engages with the front edges 30 of the shanks of the comb-bars, as is clearly shown in Fig. 9.

The operation of this form of supplementary circuit closing means is similar to that shown in Figs. 5 and 6 and described 35 above with the exception that the movements of the comb-bars are accomplished by manually moving the finger buttons 156, 157, 156' and 157'. The amount of movement is half of the distance between the 40 shanks of the spring contacts, so that two movements of a finger button will be required to move a contact point on a comb-bar from one of the shank contacts to the next. A single movement will, obviously, 45 carry the contact points to insulated points between the shank contacts thus opening the circuits. In order that the finger buttons may have the proper amount of movement 50 stop-pins 170, 171, 170' and 171' are driven into the beams 128' and 129' at proper points to limit such movement.

The leads to the contact plates 144 and 144' on the "red" side are connected to the feed wire 92 while the leads to the contact 55 plates 145 and 145' on the "green" side are connected to the feed wire 93. The circuits on the other side of the shank contacts are completed in exactly the same manner as hereinbefore described in connection with 60 the wiring diagram shown in Fig. 1.

Where, however, the design or the pattern to be produced involves the operation of nearly all of the punches, a few holes only in each set of cards being omitted, it has 65 been found that the punching operation may

be carried out with a great saving of time and with greater facility by first closing all of the circuits on one side or the other of the switch board by depressing the finger bars 70 or 71 to the full extent as shown in dotted lines in Fig. 2 whereby all of the switches on the "red" or "green" sides respectively are closed. For the purpose of preventing certain of the punches on a side from operating it is then only necessary to open the 75 corresponding individual switches on the "red" or "green" side by pressing the keys 50 or 49 respectively on the opposite side to a mid or neutral position of the cross-bars 55. 80

It is to be noted also that both the individual circuit closing means and the supplementary closing means may be used in conjunction to produce a composite pattern or design from the combined control of both 85 of the circuit closing means mentioned.

The devices herein-described and illustrated upon the accompanying drawings, while primarily intended for use in machines for the manufacture of laces, nettings 90 and similar articles, are also as fully adapted for use with any machine, controlled by jacquard cards, and used for the manufacture of other articles, such as carpets, upholstery materials and similar products. 95

By the above described invention it has become possible to perforate cards with a larger number of holes than heretofore and to also perforate similar patterns simultaneously in a plurality of cards, and therefore, while one form or embodiment of the invention has been disclosed it is to be understood that the invention is not limited particularly thereto, but comprehends also the idea of perforating any number of holes 100 simultaneously in an indefinite number of cards as well as the perforating of additional holes in any of the cards as may be selected, and it is to be further understood that many 105 changes in this invention are fully contemplated as may be within the aim and the spirit of the present invention and within the scope of the appended claims.

Having described my invention, what I claim as new and desire to secure by Letters Patent is:

1. A jacquard card perforating machine comprising in combination a punching head, punching plungers operatively mounted therein, a series of movable locking rods 120 therefor normally inactive but adapted to be moved into punch-locking position, a series of electro-magnetic devices operable to severally move said locking rods from inactive to active position and to maintain 125 them in such position during the operation of the punches, and electrical means adapted to energize said magnets, selectively, at the will of the operator.

2. A jacquard card punching machine 130

comprising in combination a punching head, 5
punching plungers operatively mounted
therein, a series of movable locking rods
therefor adapted to be moved from a nor-
mally inactive position to a punch-locking
position, electro-magnetic means adapted
to severally actuate said locking rods, elec-
trical means to selectively energize said
magnets, said means including supplemental
10 and individual selective switch members
whereby a combined operation of the
punching devices may be effected to pro-
duce a composite pattern or design.

3. A card perforating machine comprising
15 in combination a punching head, groups
of spaced punching plungers operatively
mounted therein, a corresponding series of
normally inactive locking rods adapted to
severally control the operation of each of
20 the punches in the series, a like series of
electrically energized magnets adapted,
when so energized, to severally operate said
locking rods, and electrical means to ener-
gize said magnets selectively at the will of
25 the operator, said means including devices
adapted to cut out electrical interference
between the several energized and non-ener-
gized magnets during the operation of the
machine.

30 4. A card perforating machine comprising
in combination a punching head, groups
of spaced punching plungers operatively
mounted therein, a corresponding series of
normally inactive locking rods adapted to
35 severally control the operation of each of
the punches in the series, a like series of
electrically energized magnets adapted,
when so energized, to severally operate said
locking rods, and electrical means to en-
40 ergize said magnets selectively at the will
of the operator, said means including a
single finger-operated member governing
all the electrical circuits in the series where-
by the entire series of previously energized
45 magnets and locking rods actuated thereby
may be returned to normal and inactive
position at one operation.

5. A card perforating machine comprising
50 in combination a punching head,
groups of spaced punching plungers operatively
mounted therein, a normally inactive
locking rod for each plunger, a series of
electro-magnetic means operable to severally
55 move said locking rods into active position,
circuit controlling means adapted to in-
fluence said electro-magnetic means sever-
ally and selectively at the will of the operator,
said means including switch devices
60 whereby any particular circuit after actua-
tion may be caused to immediately repeat
the operation of the same particular perfor-
ating device and simultaneously place the
other circuit-actuating devices for the re-
65 maining perforating devices in neutral or
inactive position.

6. In a card perforating device comprising
70 a pair of heads, the groups of spaced
punches in each of said heads and the lock-
ing rods therefor, the combination of an
electro-magnet for each of said rods oper-
able to move said rods when said electro-
magnets are energized and to interpose an
end of said rods in the path of said punches,
a finger operated switch board provided
75 with a number of double throw circuit clos-
ing means equal to the number of punches
in each head, and electrical circuits con-
necting the opposed circuit closing means
with said electro-magnets, whereby the clos-
80 ing of one of the opposed circuit closing
means operates to energize corresponding
electro-magnets upon both heads and the
closing of the other opposed circuit closing
means operates only to energize the electro-
magnets on one head. 85

7. In a card perforating device comprising
90 a head, the groups of spaced punches ar-
ranged in said head and the locking rods
therefor, the combination of an electro-mag-
netic means for operating said locking rods
whereby said punches are operatively con-
trolled, a finger operated switch-board for
95 selectively influencing the operation of cer-
tain of said electro-magnets and electrical
circuits connecting the last two mentioned
means; said switch-board including double
throw circuit closing means alternately op-
erative to close the circuits of the electro-
magnetic means of one head only or of the
100 electro-magnetic means in series of both
heads.

8. In a card perforating device, the com-
bination of a plurality of punch heads each
provided with similar groups of punch holes,
punch plungers reciprocably mounted there-
105 in, groups of locking rods reciprocably mov-
able in and out of the paths of said punch
plungers, a set of electro-magnets for each
group of said locking rods, a switch-board
with a set of independently operable duplex
110 switches, and circuits connecting the switches
on one side of said switch board with one
set of said electro-magnets and circuits con-
necting the switches on the other side of
said switch-board with the electro-magnets
115 of the other and with the first mentioned
circuits.

9. In a card perforating device comprising
120 a head, the groups of spaced punches ar-
ranged in said head and the locking rods
therefor, the combination of an electro-mag-
netic means for operating said locking rods
whereby said punches are operatively con-
trolled, a finger operated switch-board for
125 selectively influencing the operation of cer-
tain of said electro-magnets and electrical
circuits connecting the last two mentioned
means and means for visibly indicating the
punches controlled.

10. In a card perforating device compris- 130

ing a head, the groups of spaced punches arranged in said head and the locking rods therefor, the combination of an electro-magnetic means for operating said locking rods whereby said punches are operatively controlled, a finger operated switch-board for selectively influencing the operation of certain of said electro-magnets, electrical circuits connecting the last two mentioned means, and colored signals in said circuits for visibly indicating the selected punches operatively controlled.

11. In a card perforating device comprising a pair of heads, the groups of spaced punches in each of said heads and the locking rods therefor, the combination of an electro-magnet for each of said rods operable to move said rods when said electro-magnets are energized and to interpose an end of said rods in the path of said punches, a finger operated switch-board provided with a number of double throw circuit closing means equal to the number of punches in each head, electrical circuits connecting the opposed circuit closing means with said electro-magnets, whereby the closing of one of the opposed circuit closing means operates to energize corresponding electro-magnets upon both heads and the closing of the other opposed circuit closing means operates only to energize the electro-magnets on one head, and means for visibly indicating the punches controlled.

12. In a card perforating device comprising a pair of heads, the groups of spaced punches in each of said heads and the locking rods therefor, the combination of an electro-magnet for each of said rods operable to move said rods when said electro-magnets are energized and to interpose an end of said rods in the path of said punches, a finger operated switch board provided with a number of double throw circuit closing means equal to the number of punches in each head, electrical circuits connecting the opposed circuit closing means with said electro-magnets, whereby the closing of one of the opposed circuit closing means operates to energize corresponding electro-magnets upon both heads and the closing of the other opposed circuit closing means operates only to energize the electro-magnets on one head, and means in said circuits to differentially and visibly indicate the particular punches of each set operatively controlled.

13. In a card perforating device comprising a pair of heads, the groups of spaced punches in each of said heads and the locking rods therefor, the combination of an electro-magnet for each of said rods operable to move said rods when said electro-magnets are energized and to interpose an end of said rods in the path of said punches, a

finger operated switchboard provided with a number of double throw circuit closing means equal to the number of punches in each head, electrical circuits connecting the opposed circuit closing means with said electro-magnets, whereby the closing of one of the opposed circuit closing means operates to energize corresponding electro-magnets upon both heads and the closing of the other opposed circuit closing means operates only to energize the electro-magnets on one head, and indicating means with different characteristics corresponding with the opposed circuits closed by the double throw circuit closing means.

14. A jacquard card punching machine comprising in combination a plurality of punching heads, arranged adjacently in series, including punching plungers operatively mounted in each of said heads, locking rods severally governing the actuation of each of said punches, electro-magnetic means adapted to directly effect the actuation of said locking rods, means to simultaneously guide a card, to be punched, under each head, and a circuit controlling system governing said electro-magnetic means, whereby a plurality of cards may be simultaneously punched to effect the formation of a pattern in one of said cards which is different from but included in that of the other card.

15. In a card perforating device comprising a head, the groups of spaced punches arranged in said head and the locking rods therefor, the combination of an electro-magnetic means for operating said locking rods whereby said punches are operatively controlled, a finger operated switch-board for selectively influencing the operation of certain of said electro-magnets, a supplementary circuit controlling means for influencing the operation of certain of said electro-magnets in multiple and electrical circuits connecting said electro-magnetic means with the last two mentioned means.

16. In a card perforating device, the combination of a plurality of heads and provided with like groups of punches, a movable locking rod for each of said punches, an electro-magnet for each of said rods, an electrical circuit for each of said electro-magnets, circuit closing means for each of said circuits operable to selectively close the circuits in series with one or more of said electro-magnets, and supplementary circuit closing means operable to close a multiple of circuits in series with a similar multiple of said electro-magnets.

17. In a card perforating device comprising a head, the groups of spaced punches arranged in said head and the locking rods therefor, the combination of an electro-magnetic means for operating said locking rods

whereby said punches are operatively controlled, a finger operated switch-board for selectively influencing the operation of certain of said electro-magnets, supplemental switches for influencing certain of said electro-magnets in multiple and in progression whereby symmetrical patterns are defined, electrical circuits connecting said electro-magnetic means with the last two mentioned

means, and colored signals in said circuits 10 for visibly indicating the controlled punches.

In testimony whereof, I have hereunto affixed my signature this 19th day of February, A. D. 1919.

JAMES A. GRUNDY.
